UNITED STATES PATENT OFFICE.

CLARA E. CARR AND GEORGE D. SCOTT, OF NEW YORK, N. Y., EXECUTRIX
AND EXECUTOR OF WILLIAM S. CARR, DECEASED.

VALVE FOR WATER-CLOSET CISTERNS.

SPECIFICATION forming part of Letters Patent No. 252,734, dated January 24, 1882.

Application filed October 22, 1881. (No model.)

To all whom it may concern:

Be it known that WILLIAM S. CARR, late of the city and State of New York, deceased, did invent an Improvement in Valves for Water-Closet Cisterns, of which the following is a specification.

Valves have been made for cisterns in which a pull is used to lift the valve and allow the water to fill a small auxiliary cistern or service-box, and when the pull is relieved the valve drops, closing the passage to the service-box and opening the passage to the closet. In these cases a separate air-pipe is usually required above the service box for allowing air to pass into such service-box as the water passes out.

The said invention is made for simplifying the construction of the valve and combining therewith the air-pipe, so as not to require any separate connection; and this invention is specially adapted to hopper-closets, with depressing seats.

In the drawings, Figure 1 is a vertical section of the said cistern-valve and part of the air-pipe, and Fig. 2 is a plan at the line *x x*.

Part of the bottom of the cistern is shown at *a* and part of the service-box at *b*. This service-box is of ordinary size and shape. It is often made as a casting and bolted to the under side of the cistern.

The tube *c*, with a flange, *d*, is used for connecting the service-box to the cistern in place of bolts, as heretofore. This tube *c* passes through both top and bottom of the service-box, and a nut, *e*, serves to clamp the parts together. There should be washers between the surfaces to render the parts water-tight. The pipe *f*, that leads to the water-closet, is coupled to the lower end of the pipe *c*, or to the nut *e*, by a swell or globular coupling. The portion of the tube *c* that is within the service-box is slotted to allow the water to pass into and out of the service-box, and the interior of said tube is bored out smooth. The tube *l* slides within the tube *c*, being guided thereby, and it is to extend up as high as the level of the water in the cistern, and serves as an air-tube to the service-box,

and it may also act as an overflow-pipe to the cistern.

Around the tube *l* there is a valve, *m*, with a washer or elastic face, that rests upon a valve-seat formed by the flange *d* at the upper end of the tube *c*. Within the cylinder or tube *c* the tube *l* is slotted, and its lower end is closed to form a stopper or valve, *n*.

The wire *o* is connected to a lever, and by wires or chains either to the pull of the closet or to the seat, so that the wire *o* is lifted by the depression of the seat of the water-closet or by operating the pull. This wire *o* is attached to the cross-pins, and when the seat is depressed or the pull operated the tube *l* is raised into the position shown by dotted lines. The water from the cistern passes freely into the service-box by going through the slotted portion of said tube *l*, and the air escapes from the service-box upwardly through the tube *l*. While the seat is depressed the stopper *n* prevents the water rushing to the closet and being wasted, because such stopper is drawn up into the unslotted lower portion of the tube *c*; but as soon as the tube *l* is allowed to fall the valve *m* closes the further inlet of water from the cistern to the service-box, and the slotted portion of the tube *l*, passing below the lower end of the tube *c*, allows the water to run from the service-box into the closet, the upper part of the tube *l* still acting as an air-pipe to the service-box.

What is claimed as the invention of the said WILLIAM S. CARR is—

The slotted tube *c*, passing through the service-box and forming a valve-seat at its upper end, in combination with the tube *l*, valve *m*, and stopper *n*, the tube *l* being slotted below the valve and above the stopper, substantially as and for the purposes set forth.

Signed by us this 21st day of December, A. D. 1880.

CLARA E. CARR, *Executrix.*

GEORGE D. SCOTT, *Executor.*
